J. H. CHIDESTER.

SHIPPING CAN.

APPLICATION FILED MAR. 18, 1907.

927,223.

Patented July 6, 1909.

UNITED STATES PATENT OFFICE.

JOHN HARTFORD CHIDESTER, OF DOBBS FERRY, NEW YORK.

SHIPPING-CAN.

No. 927,223.

Specification of Letters Patent.

Patented July 6, 1909.

Application filed March 18, 1907. Serial No. 362,837.

To all whom it may concern:

Be it known that I, JOHN HARTFORD CHIDESTER, a citizen of the United States, residing at Dobbs Ferry, in the county of 5 Westchester and State of New York, have invented certain new and useful Improvements in Shipping-Cans, of which the following is a specification, reference being had to the drawing accompanying and forming a 10 part of the same.

This invention relates to metal cans and more particularly to shipping cans.

In the accompanying drawing showing 15 illustrative embodiments of this invention, in which the same reference numerals refer to similar parts in the several figures, Figure 1 is a plan view of my shipping can, a part of the cover being shown broken away to better illustrate the interior of the can and the 20 packing. Fig. 2 is a side elevation of the can, part being broken away. Fig. 3 is a detail showing the preferred means for securing the cover to the can taken on line 3—3 of Fig. 1. Fig. 4 is a vertical sectional view of 25 a modification taken on a line between adjacent stiffening rods. Fig. 5 is a detail view of a modification in which the inner body is omitted. Fig. 6 is a sectional view of a modified form of cover and packing.

30 In the illustrative embodiments of this invention shown in the drawing, 1 is a body of the can which may be made of sheet metal or any other suitable material and rolled or stamped to form the longitudinal channels or 35 flutes 2, 2. Within each channel or flute I secure a stiffening rod 3. The bottom of these rods are reduced at 4 forming a shoulder 5, the reduced portion 4 passing through 40 apertures made for them in the bottom plate 6, Fig. 4. This bottom plate is preferably stamped out of a single piece of metal and formed with a longitudinal groove 7 and flange 8 and may if desired, have a stiffening 45 rib 38 of any desired configuration formed therein. Within this annular groove 7 I snugly fit the lower end of the body 1 of the can and also of the inner body 9 when I use two bodies. The upper portion of this bottom plate 6 snugly fits against the shoulder 5 of the rods 3 so as to resist any relative movement 50 between the rod and the bottom plate, the bottom plate being held firmly against the shoulders 5 by the upset ends 11 of the reduced portions 4 of the rods 3.

55 The ends of the body portion 1 may be secured together in any suitable manner, such, for instance, as shown at 12, and when I use the inner body 9 which is preferably made of sheet steel, though other material different from the outer body may be used if desired, 60 I also secure its ends together in any suitable manner, such as shown at 13, arranging the laps or seams of the inner and outer bodies, preferably 180° apart, as shown in Fig. 1. This inner body adds materially to the 65 strength of the can and in that respect supplements the stiffening action of the rods 3, 3, though it is understood, of course, that this inner body may be dispensed with when desired as shown in Fig. 5. The upper portion 70 of these rods 3, 3, are in the preferred form shown in Figs. 1, 2 and 3 flush with the top of the can, each rod being tapped as shown at 14 for the reception of a thumb screw 15, the screw threads 16 of which co- 75 operate with the screw threads of the rods passing through apertures 17 in the cover 18 and apertures 19 in the packing 20, the shoulder 21 of the thumb screw coöperating with the upper surface of the cover in a well 80 known manner to lock the parts together and compress the packing 20, making a hermetically sealed joint. This cover 18 is preferably stamped out of a single piece of metal, 85 preferably sheet metal, and is formed with an annular groove 22 which is enlarged at intervals 23 for the reception of the ends of the bolts 3, 3. To further stiffen the can and also to have an additional bearing surface for the packing I spin or otherwise form an annular rib 24 in the inner body 9 a sufficient 90 distance below the top of the can to form an additional seat 25 for the packing 20 which here coöperates with said additional seat and with the bent portion 26 of the cover 18 to 95 form a supplemental seat. This strengthening rib is so placed as to lessen the pressure in the grooves 22 which pressure if not lessened would have a tendency to cut or mar the packing. In order to strengthen the upper portion of the can I may also use a separate ring 27, which may be secured to the bodies 1 and 9, respectively, by means of 100 rivets 28. This ring is also located just below the upper end of the can, the upper portion 29 of the ring 27 forming an additional seat for the packing 20, as shown in Fig. 4. As shown in this figure, I may, instead of 110 having the strengthening rods 3, 3 flush with the top of the can, extend them above the

body of the can and screw-thread their ends as shown at 30; using in connection with them a hollow screw-threaded thumb screw 31. The sheet packing 20 may be wood, 5 metal, vulcanized fiber, rubber or any other suitable material.

I have shown in Fig. 6 a ring packing 32 which is preferably pressed into and held securely within the groove 33 of the cover 18 10 which may of course coöperate with a suitable packing and supplemental strengthening member on the can body, as shown in Figs. 2 and 4.

My can is particularly advantageous for 15 shipping hermetically heavy merchandise, such as meat, lard, or other packing house products, essential oils, chemicals, oxids and liquids, or any other article; and is especially valuable when an air and water tight 20 container is desired which will require no extra crating for shipping, and contents of which can be easily inspected when used, for instance, as in the export trade. For handling the can I use an ordinary handle 34 secured to the body of the can by means of a 25 plate 37 which is preferably secured over the seam 12 of the outer body by means of rivets 36, 36. I may also to further strengthen the can fasten the stiffening rods 3 to the body or 30 to the body and inner body by rivets 35.

The can may be either galvanized, painted or coated with any suitable material.

Having described this invention in connection with several illustrative embodiments 35 thereof, to the details of which I do not desire to be limited, what is claimed as new and what it is desired to secure by Letters Patent is set forth in the appended claims.

1. A shipping can having a fluted body 40 portion, stiffening rods within the flutes, an inner body portion, the lower portion of the stiffening rods being reduced, forming shoulders, a bottom plate formed with an annular groove and flange and with apertures to receive the reduced portions of the rods which 45 are upset, the body portion and inner body portion being secured in the annular groove of the bottom plate, the upper portion of the rods being formed flush with the top of the 50 can and threaded, an annular rib located on the interior of the can, a packing adapted to seal the upper portions of the body and inner body to the cover, a cover having an annular groove to receive the packing and having a 55 surface to coöperate with the inner annular rib to form with the packing a supplemental seal, and a thumb screw to secure the cover to the can.

2. A shipping can having a fluted body 60 portion, stiffening rods within the flutes, an inner body portion, the lower portion of the stiffening rods being reduced forming shoulders, a bottom plate formed with an annular groove and flange and with apertures to receive the reduced portions of the rods which 65

are upset, the body portion and inner body portion being secured in the annular groove of the bottom plate, the upper portion of the rods being formed flush with the top of the can, a strengthening rib located on the interior of the can, a packing adapted to seal the upper portions of the body and inner body and the cover, a cover having an annular groove to receive the packing and having a surface to coöperate with the inner strengthening member to form with the packing a supplemental seal, and means for removably securing the cover to the can. 70

3. A shipping can having a fluted body portion, stiffening rods within the flutes, an inner body portion, the lower portion of the stiffening rods being reduced to form shoulders, a bottom plate formed with an annular groove and flange and with apertures to receive the reduced portions of the rods which 75 are upset, the body portion and inner body portion being secured in the annular groove of the bottom plate, the upper portion of the rods being formed flush with the top of the can and threaded, a strengthening rib located 80 on the interior of the can, a cover having an annular groove to receive the top of the inner and outer body portions, a packing, said annular groove being enlarged at intervals to receive the tops of the strengthening rods, 85 and thumb screws to coöperate with the screw threads in the rods to secure the cover 90 hermetically upon the can.

4. A shipping can having a fluted body portion, strengthening rods in the flutes of the body portion, the bottom of the strengthening rods being reduced to form shoulders, the upper portion of the rods being threaded, a bottom plate formed with an annular groove and apertures, the reduced portions 100 of the rods passing through the apertures and being upset, the lower end of the body portion being seated in the annular groove, a strengthening member formed on the interior of the can slightly below its top, packing 105 adapted to rest on the top of the can and upon the strengthening member, a cover to fit over the can and adapted to coöperate with the strengthening member and packing and thumb screws to coöperate with the 110 screw threads of the rods. 115

5. A shipping can having an outer body portion provided with stiffening rods, an inner body portion, a bottom plate formed with an annular groove and flange and the outer 120 and inner body portions being secured in the annular groove of the bottom plate, the upper portion of the rods being formed flush with the top of the can and threaded, an annular rib located on the interior of the can, a 125 packing adapted to seal the upper portions of the body and inner body to the cover, a cover having an annular groove to receive the packing and having a surface to coöperate with the inner annular rib to form with the 130

packing a supplemental seal, and thumb screws coöperating with said threaded rods to secure the cover to the can.

6. A shipping can having a fluted body portion, stiffening members within the flutes, an inner body portion, the lower portion of the stiffening members being reduced, a bottom plate formed with an annular groove and flange and with apertures to receive and be fastened to the reduced portions of the stiffening member, a strengthening rib located on the interior of the can, a packing adapted to seal the body and cover, a cover having an annular groove to receive the packing and having a surface to coöperate with the inner strengthening member to form with the packing a supplemental seal, and means for removably securing the cover to the can.

7. A shipping can having a stiffened outer body portion, an inner body portion, a bottom plate secured to said outer and inner body portions, an annular rib located on the interior of the can adjacent its top, a packing adapted to seal the upper portions of the

outer and inner body portions to the cover, a cover having an annular groove to receive the packing and having a surface to coöperate with the inner annular rib to form with the packing a supplemental seal, and cover screws to secure the cover to the can.

8. A shipping can having a fluted strengthened outer body portion provided with stiffening rods, an inner body portion, the lower portion of the stiffening rods being reduced forming shoulders, a bottom plate formed with an annular groove and secured to said outer and inner body portions, a rib located adjacent the top of the can, a packing adapted to seal the upper portions of the body and the cover, a cover having an annular groove to receive the packing and having a surface to coöperate with said rib to form with the packing a supplemental seal, and means for removably securing the cover to the can.
